CLAIM

USPC D21/309, 315, 356, 698, 702-705, 713,

The ornamental design for a baseball device as shown and described.

D21/715, 717, 719, 722, 780, 781, 791,

DESCRIPTION

D21/796

FIG. 1 is a top, front right perspective view of a baseball device, showing my new design;

CPC . A63B 63/004; A63B 63/083; A63B 69/0002;

FIG. 2 is bottom, rear left perspective view thereof;

A63B 69/0075; A63B 69/0079; A63B

FIG. 3 is a front view thereof;

69/0091; A63B 2069/0004; A63B

FIG. 4 is a rear view thereof;

2069/0008

FIG. 5 is a left view thereof;

See application file for complete search history.

FIG. 6 is a right view thereof;

(56) **References Cited**

FIG. 7 is a top plan view thereof;

U.S. PATENT DOCUMENTS

FIG. 8 is bottom plan view thereof;

3,623,725 A * 11/1971 Setten, Sr. A63B 69/0079
473/418

FIG. 9 is a partial enlarged view of portion 9 in FIG. 1;

D338,250 S * 8/1993 Tvedt D21/716
5,460,364 A * 10/1995 Ring A63B 69/0079
473/429

FIG. 10 is a partial enlarged view of portion 10 in FIG. 8;

D772,997 S * 11/2016 Stassi, Jr. D21/791
D814,588 S * 4/2018 Watson D21/791

FIG. 11 is a partial enlarged view of portion 11 in FIG. 4;
and,

D822,779 S * 7/2018 Gayne D21/793
D862,619 S * 10/2019 Hamilton D21/719

FIG. 12 is a partial enlarged view of portion 12 in FIG. 7.

D996,548 S * 8/2023 Feng D21/791

The dash broken lines depict portions of the baseball device.

The dot-dash broken lines depict the bounds of the detail

views. All broken lines form no part of the claimed design.
